BUILT-UP CYLINDER BLOCK FOR INTERNAL COMBUSTION ENGINES

William E. Brill, Cleveland, Ohio, assignor to General Motors Corporation, Detroit, Mich., a corporation of Delaware

Application July 12, 1937, Serial No. 153,102

6 Claims. (Cl. 123—195)

My invention relates to built-up cylinder blocks for multiple cylinder internal combustion engines comprising a plurality of parts, such as flat metallic plates and parts of special shapes, which are welded together to provide a unitary single piece cylinder block; and the principal object of my invention is to provide a cylinder block of the type aforesaid which is of simpler construction and the parts of which may be assembled and welded with greater facility and at less expense, than has heretofore commonly been the case. A further object of my invention is to provide certain improvements in and relating to the manner in which the bearings for the crankshaft of the engine are secured in place within the cylinder block, whereby the bearings are more readily accessible for replacement and repair than heretofore.

The drawings herewith submitted illustrate my invention as applied to a multiple cylinder engine wherein the cylinders are in line, with their axes parallel, and the particular features wherein my invention consists are particularly pointed out in the claims at the end of this specification.

In the drawings:

Figure 1 is a view partly in side elevation as seen from a position to the left of Figure 2, and partly in section upon a vertical longitudinally extending central plane, of a multiple cylinder engine block made in accordance with my invention.

Figure 2 is a view showing a section upon a plane at right angles to the axis of the crankshaft and passing through one of the cylinders of the engine, one of the main crankshaft bearings being shown in this view.

Figure 3 is a fragmentary view upon a plane parallel to the plane of Figure 2, and which shows a supporting member or foot forging of my invention more in detail than in Figure 2.

Figure 4 is a view showing such supporting member in perspective.

Figure 5 is a view showing a section upon a transverse plane indicated by the line 5—5, Figure 4.

Figure 6 is a view showing a detail of my invention.

Referring first to the drawings, the numerals 10 designate two oppositely arranged side plates which extend longitudinally of and throughout the length of the engine, and the upper edges of which are welded as along joints 11 to an upper deck plate 12 which likewise extends throughout the length of the engine and supports the head structure and valves not shown, and which head

is secured to the upper deck plate by stud bolts in accordance with conventional practice. The plate 12 may be a steel casing or it may be formed by rolling as I-beams and similar structural elements are commonly formed. The numeral 13 designates a lower longitudinal extending deck plate likewise welded to the side plates along longitudinally extending joints 14; and the two deck plates have openings for the upper and lower ends of the usual cylinder liners 15 whereby a cooling liquid space 16 for all the liners is provided, the side boundaries of said space being provided by the side plates 10 as will be appreciated. The ends of the side plates 10 and of the upper and lower deck plates 12, 13 are welded along joints 17 to end plates 18 which close the ends of the cooling liquid space 16; and internal transversely extending strengthening plates 19 the peripheries of which are welded to the side plates 10 and to the upper and lower deck plates 12, 13, 20 are commonly used to strengthen the cylinder blocks.

The numerals 20 designate two oppositely arranged longitudinally extending plates at the lower end of the cylinder block and which together provide the base or support therefor; these being spaced apart far enough to provide sufficient room for the cranks of the crankshaft to rotate as will be understood. These are straight members, and may likewise be formed by rolling methods. The lower ends of the end plates 18 are welded to the ends of the base plates as indicated by the numeral 21 in Figure 1. The camshaft housing 22 extends above the upper deck 12 and longitudinally of the cylinder block, 35 and is welded thereto so that the whole block forms in effect a single unitary structure, but the structural features of the camshaft housing form no part of the invention to which this present application relates. The lower end of the 40 cylinder block is closed by an oil pan 23, and the engine may be secured to a suitable foundation by bolts passing through the base plates 20 and flanges at the upper end of the oil pan, or otherwise, as is usual in marine engine installations. 45

Extending between the lower edges of the side plates 10 and the base plates 20 are a series of oppositely arranged supporting members 25 which I call "foot forgings" and which are preferably made by the use of dies and by a drop forging 50 method, although they may be steel castings. These members are arranged in pairs one at either side of each main crankshaft bearing, and they are welded in place in the cylinder block so as to be in effect integral therewith. Thus the 55

- upper ends of these members are shaped to cooperate with seats provided in the lower edges of the plates 10 and are welded in place along joints between the two at 26, and their lower ends or 5 base portions 27 are welded to the base plates 20; the inner edges of the base plates, as indicated at 28 having projections 29, Figure 6, to facilitate the welding of the base portions to said base plates.
- 10 The seats provided in the lower edges of the side plates 10 for receiving like-shaped parts of the upper ends of the supporting members 25 whereby said members are held in definite and proper positions before and during the welding 15 operation, may be of any suitable shape or outline, as their form is not material so long as the positioning of the upper ends of the supporting members 25 is secured.

Transversely arranged plates 29' are commonly 20 provided between each pair of supporting members 25 to strengthen the cylinder block and the peripheries of these plates are welded to the insides of said supporting members and to the under side of the lower deck plate 13. The lower 25 parts of the supporting members 25 are preferably of webbed formation as indicated by the cross-sectional view, Figure 5.

The numerals 30, 31 and 32 are housing plates 30 extending longitudinally of the cylinder block and welded thereto and to the camshaft housing 22 to thereby provide an integral cylinder block. These to a degree strengthen the block as a whole, although they are non-essential features 35 of the invention to which this present application relates.

The bearings for the crankshaft journals are located one between the lower base portions 27 of each pair of supporting members 25, and they are supported by and beneath said base portions; 40 each pair of supporting members serving to support a main crankshaft bearing and one pair being associated with each of the several bearings necessary to support the crankshaft of a multiple cylinder engine. Thus and referring to 45 Figure 2 which illustrates one pair of supporting members and a main crankshaft bearing supported by and between them, the numeral 33 designates a yoke-shaped bearing supporting member which is itself supported beneath the 50 base parts 27 by bolts 34 extending upwardly therethrough, and through holes in said bases, dowels 35 being provided for insuring that said member 33 shall be properly positioned relative to the bases and that the several crankshaft 55 bearings shall be kept in proper alignment.

The numeral 36 designates an upper main bearing cap, and said cap and said support 33 have semi-cylindrical seats which together provide a cylindrical seat for supporting a main bearing liner or "brass" within which a journal of the crankshaft (not shown) rotates, as is usual in crankshaft bearings. This cap is held in place by stud bolts 37 carried by the lower supporting member 33 and extending upward through said 65 cap, as shown; and the ends of said upper cap engage the inner ends of the bases 27, as at 38, thus preventing sidewise movement of the cap. The bases 27 being welded to the side plates 20 form in effect integral parts thereof, and the 70 bearing supporting members 33 being of massive construction and ribbed to provide increased stiffness, it follows that the supporting members in addition to supporting the main crankshaft bearings serve also as a plurality of ties or struts 75 extending between and whereby the side plates

20 are connected together, thus greatly strengthening the lower part or base of the cylinder block. The bearing features above referred to are present at each of the main crankshaft bearings as will be understood.

In view of the premises it follows that force due to gas pressure within the engine cylinders and acting upwardly upon the cylinder head, and force transmitted to the crankshaft bearings and base plates and acting downward, are resisted by the supporting members 25 and the side plates 10 which parts are subjected to tension by said forces when the engine is in operation. The base plates, the supporting members, the side plates and the upper deck plate 12 being welded together into a single cylinder block structure, it follows that no tie rods or bolts for securing the head to the base of the engine are employed. The welded joints between the parts enumerated provide a much stronger tension structure comprising the base plates, the supporting members, the side plates and the upper deck plate than would be provided by such tie rods, and the cross-sectional area of parts subjected to tension is many times that which would be provided by tie 25 rods, whereby a cylinder block of great strength is secured.

In an engine having a unitary cylinder block built up as hereinbefore explained, the only parts subjected to tension which are not welded into 30 the rest of the block as unitary parts thereof, are the supporting yoke members 33 for the crankshaft bearings and the bolts 34 whereby said yokes are supported from the base parts 27 of the supporting members 25. The yokes have 35 a margin of safety sufficient for the service required of them and they will seldom need to be replaced, and the bolts 34 will as a matter of course be so designed as to resist the tension to which they are subjected when the engine is in 40 use. As a matter of prudence, however, and of abundant precaution because the bolts are subjected to repeated tension stresses which are localized in and tend to weaken them, it is customary to replace the bolts after the engine has 45 been in use long enough to cause apprehension as to their margin of safety under the stresses to which they are subjected; which replacement may be conveniently accomplished as the bolts may be readily removed and replaced by new bolts 50 without disassembling or otherwise disturbing the crankshaft bearings; because in thus removing and replacing the supporting bolts the relation of the yoke members 33 to the base parts 27 is maintained by the dowels 35 so that removal and 55 replacement of the bolts does not disturb the proper relationship of the yokes to the bases 27, nor necessitate their readjustment as steps incident to removal and replacement of the bolts. Access to the bolts 34 and to the bearings when 60 their liners need replacing is afforded by hand holes in housing plates 30, 31 as will be understood.

Having thus described and explained my invention, I claim and desire to secure by Letters 65 Patent:

1. In a cylinder block for multiple cylinder engines, upper and lower deck plates extending longitudinally and throughout the length of the cylinder block and having openings for the ends 70 of cylinder liners; two side plates extending longitudinally and throughout the length of the cylinder block; base plates spaced apart from one another and extending longitudinally and throughout the length of the cylinder block; and 75

a plurality of pairs of oppositely arranged supporting members extending between the lower edges of said side plates and said base plates, all of said parts being welded together to thereby 5 form a unitary cylinder block.

2. In a cylinder block for multiple cylinder engines, upper and lower deck plates extending longitudinally and throughout the length of the cylinder block and having openings for the ends 10 of cylinder liners; two side plates extending longitudinally and throughout the length of the cylinder block; base plates spaced apart from one another and extending longitudinally and throughout the length of the cylinder block; a 15 plurality of pairs of oppositely arranged supporting members extending between the lower edges of said side plates and said base plates and all of which parts are welded together to thereby form a unitary cylinder block; and a plurality 20 of crankshaft bearings supported by and located one between the lower ends of each pair of supporting members.

3. In a unitary cylinder block for multiple cylinder engines, upper and lower deck plates extending longitudinally and throughout the length 25 of the cylinder block and having openings for the ends of cylinder liners; two oppositely arranged side plates extending longitudinally and throughout the length of the cylinder block, and which 30 side plates and deck plates are welded together; two oppositely arranged base plates extending longitudinally and throughout the length of the cylinder block; and a plurality of pairs of oppositely arranged supporting members having upper 35 ends which are welded to the lower edges of said side plates, and lower base portions which are welded to said base plates.

4. In a unitary cylinder block for multiple cylinder engines, upper and lower deck plates extending longitudinally and throughout the 40 length of the cylinder block and having openings for the ends of cylinder liners; two oppositely arranged side plates extending longitudinally and throughout the length of the cylinder block, and which side plates and deck plates are welded together; two oppositely arranged base plates extending longitudinally and throughout the length 45 of the cylinder block; a plurality of pairs of oppositely arranged supporting members having up-

per ends which are welded to the lower edges of said side plates, and lower base portions which are welded to said base plates; and a plurality of crankshaft bearings supported by and located one between the base portions of each pair of 5 supporting members.

5. In a unitary cylinder block for multiple cylinder engines, upper and lower deck plates extending longitudinally and throughout the length of the cylinder block and having openings for the ends of cylinder liners; two oppositely arranged side plates extending longitudinally and throughout the length of the cylinder block, and which side plates and deck plates are welded together; two oppositely arranged base 10 plates extending longitudinally and throughout the length of the cylinder block; a plurality of pairs of oppositely arranged supporting members having upper ends which are welded to the lower edges of said side plates, and lower base portions which are welded to said base plates; a plurality of crankshaft bearings located one between the base portions of each pair of supporting members; and means whereby said bearings are supported from and beneath the base 15 portions of said pairs of supporting members.

6. In a unitary cylinder block for multiple cylinder engines, upper and lower deck plates extending longitudinally and throughout the length 20 of the cylinder block and having openings for the ends of cylinder liners; two oppositely arranged side plates extending longitudinally and throughout the length of the cylinder block, and which side plates and deck plates are welded together; two oppositely arranged base plates extending longitudinally and throughout the length of the cylinder block; a plurality of pairs of oppositely 25 arranged supporting members having upper ends which are welded to the lower edges of said side plates, and lower base portions which are welded to the inner edges of said base plates; a plurality of bearing supporting yokes one for each crankshaft bearing; and bolts extending through the lower base portions of each pair of oppositely arranged supporting members, and through said 30 supporting yokes, for supporting said yokes from and beneath said base portions.

WILLIAM E. BRILL.
